UNITED STATES PATENT OFFICE.

JAMES W. ARROWSMITH, OF MORRISTOWN, NEW JERSEY.

INSTEP-SUPPORT.

1,079,736.

Specification of Letters Patent.

Patented Nov. 25, 1913.

Application filed October 22, 1909. Serial No. 523,960.

To all whom it may concern:

Be it known that I, JAMES W. ARROWSMITH, a citizen of the United States, and a resident of Morristown, in the county of Morris and State of New Jersey, have invented certain new and useful Improvements in Instep-Supports, of which the following is a specification.

The improvements relate to devices for supporting the arch of the human instep when the same is weakened or injured from any cause and for restoring the same to its normal condition when flattened or otherwise deformed, as by the progress of the disease called flat-foot. Their objects are, among others, to provide a strong, light and durable support of this character which may be fitted to various degrees or kinds of deformity; to provide means for absorbing to a certain extent the shock to the system of the wearer at each step taken due to the inelastic condition of the natural arch and at the same time permit the support of the said arch and the treatment of the deformity to be carried on, and to so construct and arrange the parts designed for the carrying out of the above objects that they will cooperate with one another in various ways.

The invention consists in the construction, combination and arrangement of parts hereinafter described and claimed and illustrated in the accompanying drawings.

In the said drawings Figure 1 is a plan of a covered instep support embodying the improvements. Fig. 2 is an underside view of the same. Fig. 3 is a vertical longitudinal section on the line 3—3 of Fig. 2 looking in the direction indicated by the arrow.

The plate A consists of a body portion adapted to fit the normal undersurface of the instep arch and a side portion adapted to fit the inside of the said normal arch. At the forward end the plate extends to the anterior part of the metatarsus, but the rear portion is cut away so that it does not reach the base of the calcaneum or os-calcis, the rear edge being oblique to the longitudinal axis of the plate, and the plate being thinner along this edge than in the body portion.

The cover B is of the usual form and consists of a non-metallic substance, such as leather, molded to fit the plate, extending beyond the same a suitable distance and secured thereto at points near the line of junction of the body and side portion by rivets or like fastenings C C'.

Above the rear portion of the plate A and extending backward therefrom in substantial conformity to the shape and area of the heel portion of the cover is an auxiliary plate 60 D which may be of leather or other non-metallic substance or of light flexible metal as desired. This plate is secured to the main plate and cover by the rivet C' passing through all three of the parts and also by the 65 line of stitching E by which its forward edge is attached to the cover B.

Between the heel portion of the cover and the plate D a spring or cushion F is located. This cushion may be made of sponge, rubber 70 or other suitable material having a high degree of elasticity, and is secured in position by the rivet C' which passes through it at its forward part. This cushion F is beveled as it approaches the plate A, as shown at F' 75 and the plate is also beveled at its upper side along the rear edge so that the thickness of the plate and the cushion at the point where they overlap is not greater than the thickness of the cushion alone back of that point. The 80 cushion is preferably cemented or otherwise attached to the heel portion of the cover and to the auxiliary piece or plate D.

It will be seen that in the construction herein described and shown the ordinary 85 metal support is supplemented by a cushion for one of the extremities of the instep arch, and the parts so constructed and arranged that the metal support has sufficient base length and other proportions to perform its 90 functions while at the same time the cushion acts independently as well as in coöperation with the said support, within the area to be supported.

What I claim is:—

1. The combination of a metallic instep arch support consisting of a plate conforming to the instep arch and adapted to extend from the anterior portion of the metatarsus to the base of the calcaneum on 100 one side and being cut away at its rear end on a line running from one side of the plate to the other forward of the said calcaneum base, the cover secured to the upper side of said plate near its rearmost extremity and 105 extending back of the same to a point behind the calcaneum, fastening means by which the said cover is so secured, a piece of flexible material secured to the plate by the same fastening as the cover and extending 110 from that point to the back of the calcaneum, and a cushion of elastic material also

secured to the plate near its rearmost point and extending backward beneath the base of the calcaneum.

2. The combination of a metallic plate 5 adapted to fit the arch of the instep, and having its rear edge cut away from one side to the other so that one side edge is within the base of the instep arch, a cover secured thereto, extending backward beneath the 10 heel, a heel piece of flexible material co-extensive with the heel portion of the cover and secured thereto at its forward edge, a cushion of elastic material between the heel portion of the cover and the heel piece, and 15 a single fastening extending through the cover, cushion and heel piece and through the plate near its rearmost extremity whereby the said parts are all secured together.
3. The combination of a metallic instep 20 arch support consisting of a plate conforming to the instep arch and extending from the anterior portion of the metatarsus to the base of the calcaneum on one side along one longitudinal edge and to a point forward of 25 the same along the opposite edge, the back edge of the said plate being oblique to the longitudinal axis of the same, a cover secured to the upper side of the said plate near its rearmost extremity and extending 30 back of the same to a point behind the calcaneum, and a piece of flexible material secured to the plate between the cover and the plate and extending from that point to the back of the calcaneum, said piece of

flexible material having a forward portion 35 of reduced thickness.

4. A device of the character described comprising in its construction an elastic non-metallic heel cushion, a metallic arch support extending from a point at the forward portion of the heel base to a point beneath the ball of the foot, and conforming substantially to the instep arch between these points, the heel cushion having its major portion non-co-incident with the plate and 45 the plate having its major portion non-co-incident with the cushion.

5. A device of the character described comprising in its construction an elastic non-metallic heel cushion, a metallic arch support extending from a point at the forward portion of the heel base to a point beneath the ball of the foot and conforming substantially to the instep arch between these points, the heel cushion having its major 55 portion non-co-incident with the plate and the plate having its major portion non-co-incident with the cushion, and a portion of the rear edge of the plate being forward of the cushion.

Witness my hand this 19th day of October, 1909, at the city of New York, in the county and State of New York.

JAMES W. ARROWSMITH.
